UNITED STATES PATENT OFFICE

2,430,021

TIE FORM

Thomas O. Johnson, Richmond, Calif.

Application October 18, 1945, Serial No. 623,046

1 Claim. (Cl. 2—157)

1

My invention relates to improvements in necktie forms and has for an object to provide means for holding a tie in fixed position.

Another object of the invention is to provide a tie form adapted to hold the depending loose ends properly spread.

Other features and advantages will become more readily apparent from the following description and the accompanying illustrative drawings in which:

Figure 1 is a rear elevational view of a four-in-hand or other like tie embracing my invention,

Figure 2 is a front elevational view thereof,

Figure 3 is a side view of my device detached from the tie,

Figure 4 is a sectional view taken on line 4—4 of Figure 2, and

Figure 5 is an end view detail of one member of the device.

In the above drawings as well as in the specification to follow, the same characters of reference indicate the same parts throughout.

In the drawings, 10 indicates my invention which consists of a vertically disposed arcuate wire 11, to which is attached intermediately thereof a transverse wire 12. The upper end 13, of the wire 11, is returned upon itself as at 14, being slightly spaced from the part 13, and is then returned again as at 15, and terminates in a relatively large ring 16. The lower end of wire 11 is bent into a ring 17, and terminates in a pin point 18. The wire 12 is provided at its outer ends 19 and 20, both of which terminate in respective pins 21 and 22, with rings 23 and 24.

In using the above described device the ring 16 is slipped under a fold of a four-in-hand tie as indicated in Figures 1 and 2, and the hook device 25, formed by the bends 14 and 15, is caught under a fold of the tie, whereby the device is held to the knot 26, of the tie from the rear or inner portion thereof. The pin 18 is then projected into the tail portion 27, of the tie and the wings 28 and 29, thereof are spread apart and its edges 30 and 31 engaged by the pin points 21 and 22, whereby the entire tie is held in proper and uniform position as indicated in Figure 2.

As above stated, the member 11 is arcuate to

2

both conform somewhat to the shape of the wearer's breast and also to hold the body of the tie out of contact with the person. I also may provide the connection 32, between the cross wire 12 and the vertical wire 11, with a vertical bore 33, whereby the member 32 may be vertically moved up or down upon member 11, for suitable adjustment thereof relative to a particular tie, the arcuate member 11 passing through the vertical bore will bind therein and hold the member 32 in adjusted position.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention, that which I claim as new and desire to procure by Letters Patent is:

25 A tie form comprising a vertically extending bowed bar, a keeper slidably mounted thereon, a transversely extending bowed bar supported in fixed position upon said keeper, loops formed at the ends of said bars extending rearwardly therefrom, and necktie engaging pointed extremities formed on said loops.

THOMAS O. JOHNSON.
